W. H. JOHNSON,
LUBRICANT SEGREGATING MEANS FOR INVERTED INTERNAL COMBUSTION ENGINES.
APPLICATION FILED FEB. 20, 1920.
1,362,006. Patented Dec. 14, 1920.

Inventor,
Willis H. Johnson, by
G. C. Kennedy,
Attorney.

UNITED STATES PATENT OFFICE.

WILLIS H. JOHNSON, OF WATERLOO, IOWA.

LUBRICANT-SEGREGATING MEANS FOR INVERTED INTERNAL-COMBUSTION ENGINES.

1,362,006.

Specification of Letters Patent. Patented Dec. 14, 1920.

Application filed February 20, 1920. Serial No. 360,048.

To all whom it may concern:

Be it known that I, WILLIS H. JOHNSON, a citizen of the United States of America, and a resident of Waterloo, Blackhawk county, Iowa, have invented certain new and useful Improvements in Lubricant - Segregating Means for Inverted Internal-Combustion Engines, of which the following is a specification.

10 My invention relates to improvements in lubricant segregating means for inverted internal combustion engines, and the object of my improvement is to supply such an engine with means for diverting fluid lubricant discharged from moving parts above the cylinder and piston to be in greater amount segregated from said cylinder and conveyed to an independent receptacle, from which it may be drawn without admixture with or 20 contamination by the condensed fluid fuel of the engine.

This object I have attained successfully by the means which are hereinafter described and claimed, and which are illustrated in the 25 accompanying drawing, which is a vertical central longitudinal section of an inverted internal combustion engine constructed to include my improvement.

The engine may be of any type pertaining 30 to the class wherein a piston is reciprocable through an open-ended cylinder 9. As commonly employed, such engines when the cylinders are placed upright, have their combustion-chambers located at the top, with 35 the piston-rod depending in each case toward a crank-shaft whose cranks are inclosed in a crank-case below the cylinder. In this class of engines, a certain proportion of unconsumed condensed fuel-oil, such as 40 kerosene or other mineral hydrocarbon, can work downwardly between the piston and the cylinder-walls from the combustion-chamber, and mix with and contaminate the lubricating-oil which is used in the crank- 45 shaft bearings and discharged thence into the lower and receiving part of the crank-case. The mixed oils are hard to separate, in order to permit of again using the lubricating-oil free from such contamination.

50 To prevent this mixing of the fuel-oil with the fluid lubricant, I have inverted the engine, as shown, to locate the internal-combustion chamber of the cylinder at its lower end at 7, so that the piston 8 may reciprocate 55 in the cylinder 9 with its piston-rod extending upwardly to the crank-shaft which

traverses the crank-case 2 above the cylinder.

The crank-case is constructed with its side-walls 1 considerably wider apart than the diameter of the cylinder 9 below, so that the bottom of the crank-case at 3 may be horizontally disposed surrounding the open upper end 4 of said cylinder and spaced below it. A receptacle 6 may be formed integral with said casing and extending below it, to 60 communicate therewith by means of an opening 5, said receptacle having a vent at the bottom supplied with a screw-plug whereby the contents may be evacuated when desired.

It will be observed that when lubricating- 70 oil is supplied to the bearings of the moving parts within said crank-case, the oil which is thrown off from these rapidly moving parts will tend to be dispersed downwardly and outwardly in direction into the receptacle or 75 pan formed by the depressed bottom 3 of the crank-case, and drained thence through the opening 5 into the well or vessel 6, without admixture in any way with condensation products of the engine fuel, or any carbon or 80 other contamination due to the consumption of fuel in the combustion-chamber or the action of the mechanical elements of the engine. This lubricant is therefore suitable 85 for reuse at once without need for purification.

A sufficient quantity of the lubricant descends into the open upper end of the cylinder 9 to lubricate the piston without excess. No kerosene can work from the combustion-chamber 7 into the crank-case to contaminate the lubricant, and this improvement therefore renders such an engine very suitable for employment on tractors or the like vehicles, where motors which consume 90 heavy hydrocarbons are in use.

Having described my invention, what I claim as new, and desire to secure by Letters Patent, is:

1. In an internal combustion engine, a 100 vertically disposed cylinder with a combustion-chamber at its lower end and a crank-casing surrounding its upper end, and having a piston reciprocable in said cylinder, said casing being formed with means for segregating part of the fluid lubricant delivered from the mechanisms in the casing and separate from the said cylinder.

2. In an internal combustion engine, of 110 the inverted type having its combustion chamber below the piston, means located at the upper end of the engine cylinder and

spaced below it, adapted to receive and divert lubricant delivered downwardly from moving parts above said cylinder.

3. In an internal combustion engine, an inverted upright cylinder, a reciprocable piston therein with piston-rod extending upwardly, a crank operatively connected to said piston-rod above the open upper end of said

cylinder, and a receiving vessel surrounding the open upper end of said cylinder with its bottom spaced below said open upper end, said vessel having means for removing its contents.

Signed at Waterloo, Iowa, this 28th day of January, 1920.

WILLIS H. JOHNSON.
